UNITED STATES PATENT OFFICE

2,576,726

SUCTION CLEANER

Louis E. Segesman, Canton, Ohio, assignor to The
Hoover Company, North Canton, Ohio, a corpora-
tion of Ohio

Application October 3, 1946, Serial No. 701,030

7 Claims. (Cl. 183—58)

1

The present invention relates to suction cleaners in general and more particularly to a new and improved filter-cleaning mechanism in a suction cleaner.

An object of the present invention is to provide a new and improved suction cleaner. Another object is to provide a new and improved filter-cleaning device in a suction cleaner. Other objects and advantages of the invention will be apparent from the following specification and drawings, wherein:

Figure 1 is a longitudinal vertical section through the cleaner constructed in accordance with one embodiment of the invention;

Figure 2 is a top plan view of the filter-shaking mechanism disclosed in Figure 1;

Figure 3 is a side elevational view of another embodiment of the filter-shaking mechanism; and

Figure 4 is a top view of the filter-shaking mechanism shown in Figure 3.

The embodiment of the invention disclosed in Figures 1 and 2 comprises a casing 10 closed at its exhaust end by an end cap 11 having an outlet port 12 adapted to receive the cleaner end of an unshown dusting tool hose which is provided at its opposite end with a surface-cleaning tool in a manner well known in the art. The suction end of the casing is closed by a removable end cap 13 provided with an inlet port 14 adapted to receive the cleaner end of a dusting tool unit in the same manner as the outlet port 12. End cap 13 is removably attached to the casing 10 by being provided at its lower end with a protruding lip 15 which seats within a pocket 16 formed at the end of a bracket 17 mounted on the bottom of the casing 10. An overcenter type latch 18 is mounted on the top of the casing 10 and cooperates with the end cap 13 to force it against the end wall or face 19 of the casing 10, and a seal 20 prevents leakage of air therebetween.

Casing 10 is slidably supported upon longitudinally extended runners 21 terminating in the plane of the front end wall 19 of the casing 10, and which enable the operator to pull the machine over the supporting surface by means of the force exerted through the dusting tool hose. There is also provided along the top of the cleaner casing a carrying handle 22 and a switch 23.

Within the casing 10 near the exhaust end cap 11 is a motor 25 having a shaft 26 extending into a fan chamber 27 where it carries rotatable fans 28 separated by fixed guide vanes 29 mount-

2

ed on the fan chamber. The fan chamber is formed with an intake port 30 and with exhaust ports 31. The motor-fan unit is supported at its forward end by a resilient rubber ring 32 which lies around the forward edge of the fan chamber 27 and is supported by a fixed bulkhead 33 mounted in the casing 10 and provided with apertures 37. Supported upon the bulkhead 33 is a filter frame 34 having a plurality of apertures 35 and cooperates with a portion 36 of the bulkhead 33 to provide a chamber in which is disposed a filtering material 38 for filtering the air prior to passing it through the inlet 30 into the fan chamber 27. At its opposite end the motor-fan unit is carried by a resilient ring 40 mounted in a perforated bulkhead 41 fixedly secured to the casing 10 by screws 42.

A dirt-filtering bag 44 is disposed between the motor-fan unit and the front end cap 13 and has an annular side wall 45 and a closed end wall 46, while the open end of the bag 44 is secured to a bag ring 47 disposed adjacent the front end wall 19 of the casing 10, and an annular flange 48 on the end wall 19 defines the opening to the filter bag 44. The closed end 46 of the bag 44 is supported on a circular frame 50, and secured to the latter by means of a nut and bolt connection 51 is a substantially U-shaped bracket 52 having a bar 53 extending diametrically of the bag end wall 46 and terminating in forwardly extending arms 54 and 55 extending along the bag side wall 45.

A U-shaped lever 60 has its arms 56 and 58 pivotally supported at their lower ends upon a rod 61 mounted in a frame 59 attached to the casing 10, and the upper ends of the arms 56 and 58 are respectively pivotally mounted on the bracket arms 55 and 54. A link 57 is pivotally connected to the bracket arm 54 and the frame 59. The pivoted link 57 and arm 58 are along one side of the bag and equal in length and have their pivot points at their opposite ends spaced equidistant so that as the link 57 and lever 60 pivot, the bracket 52, bag-supporting frame 50, and bag end wall 46 will at all times remain parallel with the casing front wall 19 and the open end of the bag 44. Disposed about the pin 61 are a pair of torsion springs 62 having one of their ends resting upon the lever 60 and their opposite ends abutting lugs 63 on the frame 59 to at all times urge the link 57, the arms 56 and 58, and the bag-supporting frame 52 rearwardly within the casing 10 to draw the bag 44 taut.

The filter-vibrating mechanism shown in Figures 1 and 2 is disposed centrally below the filter

bag 44 along the bottom wall of the casing and comprises a U-shaped guide 70 having an inclined top wall 71 and side walls 72-72 provided with a plurality of tabs 73 which are attached to the casing 10. Formed in the top wall 71 is a slot 74 in which is movably disposed an engaging member 75 having a substantially vertical face 76 and an inclined face 77. The member 75 is rigidly attached to a flattened portion 78 of a rod 79, the latter being slidably mounted at its front end in an opening provided in a wall 80 depending from the guide top wall 71 while the rear end of the rod 79 is slidably supported in a member 81 attached to the casing 10. A handle 82 is attached to the rod 79 and is disposed in a recess 83 sealed from the interior of the casing by portions of the bulkhead 33 and filter frame 34, and the member 81. A portion of the handle 82 projects through a slot 84 in the casing 10 for the operator to grasp the handle 82 and reciprocate the rod 79 and the member 75.

A U-shaped connecting member 85 has its opposite ends 86-86 pivotally connected to the lever arms 56 and 58 and has a center portion 87 adapted to abut the face 76 on the member 75 to collapse the bag 44. A torsion spring 88 is arranged about each pivoted end 86 of the member 85 and operates to at all times urge the center portion 87 of the member 85 into sliding engagement with inclined surfaces 89-89 disposed along opposite sides of the slot 74.

In normal cleaning operation of the embodiment shown in Figures 1 and 2, the motor-fan unit draws dirt-laden air through a suitable dusting tool unit connected to the intake port 14 and into the filter bag 44. Filter 44 removes from the air stream the suspended foreign material and the clean air passes outwardly through the walls of the bag and into the space defined by the surrounding main casing 10. Before entering the fan chamber, the air first passes through the secondary filter 38 to remove any dirt particles which have escaped through the filter bag 44. The cleaned air passes into the fan system at the intake 30 of the fan chamber 27 and is discharged through the exhaust ports 31 into the space within the casing 10 surrounding the motor 25. The air then passes through the perforations 90 in the bulkhead 41 and through the outlet 12 into the surrounding atmosphere. This operation can continue until such time as accumulation of foreign material within the filter bag 44 reduces the effective suction of the machine thereby reducing cleaner efficiency and making it desirable to remove the foreign material from the bag.

The bag-cleaning operation comprises initially removing the end cap 13 by manipulating the latch 18 to expose the flat end wall 19 of the casing 10 and the opening 48 to the filter bag 44. The cleaner is then up-ended into filter-cleaning position so that the end plate 19 lies flush upon a supporting surface which is preferably provided with a paper or the like for receiving the dirt to be removed from the bag 44.

To dislodge the foreign material from the bag, the operator grasps the handle 82 and exerts a downward force towards the front end of the cleaner casing causing movement of the engaging member 75 which thereupon moves towards the casing front end wall 19 in the slot 74. Movement of the member 75 causes the center portion 87 of the member 85 to slide along the inclined surfaces 89-89 and effects pivotal movement of the bag-supporting arms 56, 57, and 58

attached to the bag bracket 52. Movement of the members 75 and 85 causes the rear end wall 46 of the bag to be collapsed towards the front end of the cleaner casing against the force exerted by the torsion springs 62-62, and due to the arrangement of the arms 57 and 58 the rear end wall 46 of the bag is shifted in planes which are parallel to the front end wall 19 of the cleaner casing and thereby collapses bag 44. Upon continued movement of the member 75 within the slot 74, the portion 87 of the yoke 85 moves along the upwardly inclined surfaces 89-89 until the top of the face 76 of the member 75 rides beneath the inclined surfaces 89-89 whereupon the member 85 is disengaged from the member 75 and permits the springs 62-62 to jerk bag frame 50 and the end 46 of the bag back to their original positions in which the bag is taut. This abrupt vibration of the bag effects the dislocation of adhering foreign material which thereupon falls downwardly through the central aperture 48 of the casing end wall 19 to come to rest upon the underlying supporting surface or the paper placed thereupon to receive the dislodged dirt.

After the bag has returned to its normal taut condition, the operator exerts an upward force on the handle 82 to move the rod 79 and the member 75, and toward the end of this movement the inclined face 77 of the member 75 contacts portion 87 of the yoke 85 and the latter slips along the face 77 until it rides thereover into engagement with the face 76 of the member 75 to place the filter-cleaning mechanism in position for another bag-cleaning operation.

After the bag has been adequately cleaned, the operator need only tilt the machine back to its horizontal position, replace the cover 13, and the machine is again ready for performing its normal cleaning function.

The embodiment of the bag-shaking mechanism disclosed in Figures 3 and 4 is arranged in the cleaner casing 10 with respect to the filter bag 44 in the same manner as shown in Figures 1 and 2, and comprises a bag shaker base 95 on which the link 57 and the arms 56 and 58 of the lever 60 are pivotally mounted to support the rear end of the bag 44. Centrally disposed on the base 95 below the bag 44 is a guide 96 provided with a top wall 98 and side walls 99-99 having angular feet 94 which are attached to the frame 95 by a plurality of rivets 100. Formed in the top wall 98 is a releasing member 101 having an inclined face 102, and adjacent the latter is a slot 103 formed in the top wall 98 for movably receiving an engaging member 104 having a substantially vertical face 105 and an inclined face 106, and the engaging member 104 is rigidly attached to a rod 108, the latter being slidably mounted in the guide end wall 122 and the member 110 attached to the bottom wall of the cleaner casing 10. A handle 111 is attached to the rod 108 and is disposed in a recess 112 sealed from the interior portion of the casing by the member 110. A portion of the handle 111 projects through a slot 112 in the casing 10 for the operator to grasp the handle 111 and reciprocate the rod 108 and the engaging member 104.

A U-shaped connecting member 113 has its opposite ends 114 pivotally connected to the lever arms 56 and 58 and has a center portion 115 on which is rotatably mounted spaced rollers 117 adapted to engage the surfaces 116-116 formed on the top wall 98 on opposite sides of the slot 103. A portion 120 of the connecting member 113 is disposed between the spaced rollers 117

and is adapted to abut the face 105 of the engaging member 104. A torsion spring 88 is arranged about each end 114 of the connecting member 113 and operates to at all times urge the rollers 117 into engagement with the surfaces 116 and to maintain the portion 120 of the connecting member 113 in engagement with the face 105 of the engaging member 104. A spring 121 is arranged about the rod 108 interiorly of the guide 96 between a bracket 109 forming part of the engaging member 104 and the end wall 122 and functions to return the push rod 108, the engaging member 104, and the handle 111 to their normal positions shown in Figure 3.

In operating this embodiment of the invention, the cleaner performs its normal cleaning function as previously described, and when it is desired to dislodge the foreign material from the bag 44 the cleaner casing is up-ended into bag-shaking position in the same manner as described in connection with Figures 1 and 2.

To dislodge the foreign material from the bag, the operator grasps the handle 111 and pushes it downwardly towards the casing front wall 19 causing the rod 108 and the engaging member 104 to move downwardly in the guide 96. Downward movement of the engaging member 104 causes the rollers 117 to move along the surfaces 116—116, the portion 120 of the connecting member 113 and the rear end 46 of the bag to move towards the front end of the cleaner casing with the result that the bag 44 is collapsed. Upon continued downward movement of the handle 111, the rollers 117 come in contact with the inclined surface 102 of the releasing member 101, and the rollers 117 move up the inclined surface 102 until they ride over the top of the member 104 to disengage the yoke portion 120 from the face 105 to permit the torsion springs 62 to jerk the bag frame 50 and the bag back to their initial positions. The operator then removes his hand from the handle 111 and the spring 121 functions to return the handle 111 to its normal position, and upon movement of the rod 108 back to its normal position, the inclined face 106 contacts the yoke portion 120 and the latter moves along the inclined surface 106 until it rides off the top thereof and is forced downwardly into the position shown in Figure 3 by the springs 88, and the portion 120 of the connecting member 113 abuts the face 105 of the engaging member 104 so that the bag-shaking mechanism is in position for another cleaning operation. This bag-shaking operation should be repeated a plurality of times to insure complete cleaning of the bag 44.

I claim:

1. In a suction cleaner, a casing, a filter in said casing, filter-supporting means, resilient means normally urging said filter-supporting means in one direction to maintain said filter in one position, filter-shaking means including movable engaging means, connecting means for connecting said filter-supporting means to said engaging means, said engaging means applying a force through said connecting means to collapse said filter in opposition to said resilient means, releasing means for releasing said connecting means from said engaging means after said filter is collapsed to permit said resilient means to return said filter to said one position, guide means forming part of said release means and having a slotted portion receiving said engaging means to guide the latter during its operation,

and actuating means for moving said engaging means and said releasing means with respect to each other.

2. In a suction cleaner, a casing, a filter in said casing, filter-supporting means, resilient means normally urging said filter-supporting means in one direction to maintain said filter in one position, filter-shaking means including engaging means, connecting means connecting said filter-supporting means to said engaging means, said engaging means applying a force through said connecting means to said filter to collapse said filter in opposition to said resilient means, releasing means for releasing said connecting means from said engaging means after said filter is collapsed to permit said resilient means to return said filter to said one position, stationary guide means extending between said engaging means and releasing means, said guide means having a surface upon which said connecting means is moved by said engaging means until disconnected by said releasing means, and actuating means for moving said engaging means with respect to said releasing means.
3. In a suction cleaner, a casing, a filter in said casing, filter-supporting means, resilient means normally urging said filter-supporting means in one direction to maintain said filter in one position, filter-shaking means including engaging means, connecting means connecting said filter-supporting means to said engaging means, said engaging means applying a force through said connecting means to said filter to collapse said filter in opposition to said resilient means, releasing means for releasing said connecting means from said engaging means after said filter is collapsed to permit said resilient means to return said filter to said one position, guide means between said engaging means and releasing means, said guide means having a surface upon which said connecting means move to said releasing means, means at all times urging said connecting means into engagement with said surface of said guide means, and actuating means for moving said engaging means with respect to said releasing means.
4. In a suction cleaner, a casing, a filter in said casing, filter-supporting means, resilient means normally urging said filter-supporting means in one direction to maintain said filter in one position, filter-shaking means including engaging means, connecting means connecting said filter-supporting means to said engaging means, said engaging means applying a force through said connecting means to said filter to collapse said filter in opposition to said resilient means, releasing means for releasing said connecting means from said engaging means after said filter is collapsed to permit said resilient means to return said filter to said one position, stationary guide means between said engaging means and releasing means for guiding said connecting means to said releasing means, actuating means for moving said engaging means with respect to said releasing means, and means in said guide means for returning said actuating means to normal position.

5. In a suction cleaner, a casing, a filter in said casing, filter-supporting means movably mounted alongside said casing and projecting therefrom for connecting one end of said filter, resilient means normally urging said filter-supporting means in one direction to maintain said filter in one position, filter-shaking means including engaging means movable in a rectilinear path

alongside said casing, connecting means connecting said filter-supporting means to said engaging means, said engaging means during said rectilinear movement applying a force from alongside said casing through said connecting means to said one end of said filter to collapse said filter in opposition to said resilient means, releasing means alongside said casing for releasing said connecting means from said engaging means after said filter is collapsed to permit said resilient means to return said filter to said one position, guide means between said engaging means and releasing means, said guide means having a surface along which said connecting means move to said releasing means, and actuating means for moving said engaging means in said rectilinear path with respect to said releasing means.

6. In a suction cleaner, a casing, a filter bag in said casing, bag supporting means movably mounting said filter bag on said casing, bag moving means displaceably mounted on said casing, connecting means spanning said bag for connecting said bag supporting means to said bag moving means and displaceable with the latter, disconnecting means mounted in stationary relation to said casing for engagement with said connecting means to release the latter from said bag moving means, actuating means for displacing said connecting means and bag moving means to collapse said filter bag and shake the latter, and means for returning said filter bag to a normal position.

7. In a suction cleaner of the tank type, a casing, a filter in said casing, a removable cover closing an open end of said casing, said open

5 end adapted to rest upon a supporting surface with said cover removed to position said filter in filter cleaning position, filter supporting means movably mounting said filter in said casing for movement with respect to said open end of said casing, filter moving means displaceably mounted on said casing and detachably connected with said filter supporting means, disconnecting means mounted in stationary relation with said casing for engagement with said filter moving means to release the latter from said filter supporting means to permit return of said filter to another position, actuating means for displacing said filter moving means to move said filter with respect to said open end of said casing to shake said filter and remove dirt therefrom for disposing of the dirt to said open end, and to shift said filter moving means into engagement with said disconnecting means to release said filter supporting means, and means for returning said filter to said another position with respect to said open end.

LOUIS E. SEGESMAN.
